UNITED STATES PATENT OFFICE.

HEINRICH ZOELLY, OF ZURICH, SWITZERLAND.

ELECTRIC-DRIVEN REFRIGERATING-MACHINE.

1,263,633.

Specification of Letters Patent. Patented Apr. 23, 1918.

Application filed June 13, 1917. Serial No. 174,560.

To all whom it may concern:

Be it known that I, HEINRICH ZOELLY, a citizen of the Republic of Switzerland, residing at Zurich, Switzerland, have invented

5 certain new and useful Improvements in Electric-Driven Refrigerating-Machines; and I do hereby declare the following to be a full, clear, and exact description of the invention, such as will enable others skilled 10 in the art to which it appertains to make and use the same, reference being had to the accompanying drawing, and to letters or figures of reference marked thereon, which form a part of this specification.

15 This invention relates to improvements in electrically driven plants adapted to be used exclusively for refrigerating purposes or for making ice, or again for refrigerating and ice making at the same time.

20 One object of the invention is to provide an improved refrigerating machine of this character particularly suitable for households, hotels, cafés, restaurants, provision merchants and the like, which is of simple

25 and compact design and forms a completely inclosed, airtight arrangement, so that it does not require any attendance.

A further object of the invention is to provide an improved refrigerating machine 30 of the character referred to in which belts, valves, stuffing boxes and the like are entirely done away with.

To the attainment of these ends and the accomplishment of other new and useful improvements the invention, as will appear, 35 consists in the suitable combination and arrangement of the several parts hereinafter more fully described and claimed and shown in the accompanying drawing, illustrating 40 as an exemplification of the invention, a refrigerating plant.

In the drawing:

Figure 1 is a vertical longitudinal sectional view of the refrigerating machine.

45 Fig. 2 shows a detail on an enlarged scale and in a section on the line II—II of Fig. 3.

Fig. 3 is a section on the line III—III of Fig. 2.

Fig. 4 is a section on the line IV—IV of 50 Fig. 1, and

Fig. 5 shows the fitting of the machine in an ordinary refrigerator.

In the embodiment of the invention shown in the drawing, 1 denotes a vertically ar- 55 ranged shaft to the upper end of which is fixed the rotor 2 of an electromotor. 3 de-

notes the stator of this electromotor surrounding the rotor 2. Fitted within the central bore of this stator 3 is a thin steel-cap 4 of low electric conductivity and put over 60 the rotor 2. The lower rim of this cap 4 rests in a groove of the upper rim 5^a of a casing 5, and is calked into this groove in an airtight manner by means of a ring 5^b, so that the cap 4 and the casing 5, form a 65 unitary whole. The electromotor 2, 3 is mounted in a casing 11 provided with a detachable cover 12.

The lower end of shaft 1 is shaped into a disk crank 6. The latter drives the piston 70 rod of a piston 7 in a cylinder 8. The parts 7 and 8 form the principal parts of the compressor which is provided with trunnions 9 and mounted in a cylindrical casing 10, so that it oscillates by the revolving of the 75 crank pin 6. The casing 10 is arranged coaxially to the electromotor 2, 3. The central, hub-like part 13 of the casing 10 acts as a bearing for the driving shaft 1.

The casing 10, within which is fitted said 80 compressor 7, 8 arranged below the electric motor 2, 3 is subdivided into three chambers 14, 15, 16 of which chamber 14 forms the suction chamber, while the space 15 forms the bottom pressure chamber and the space 85 16 the top pressure chamber, the latter acting at the same time as a tank for the lubricating oil. The interior of cylinder 8 may be put into communication with the bottom pressure chamber 15 by means of slots 17 90 and with the suction chamber 14 by means of slots 18 provided in the cylinder 8 and slots 19 provided in a wall of the casing 10. The slots 18 and 19 open from time to time in consequence of the oscillating movement 95 of the cylinder 8. 17¹ denotes flap pressure-valves arranged beneath the slots 17. A rising pipe 20 leads from the lowermost part of the bottom pressure chamber 15, into which exhausts the compressor, to the top 100 pressure chamber 16 arranged above said chamber 15.

The compressor casing 10 is surrounded by the casing 5 hereinbefore referred to, a space 22 being left between these two casings. This ring space 22 communicates with the top pressure chamber 16 by means of a conduit 21.

23 denotes the refrigerator arranged below the condenser casing 5 and coaxially to the latter. This refrigerator forms in the present instance also the bottom of the casing

10 and incloses together with the bottom of the compressor casing 10 the condenser chamber 24. In the central portion of the refrigerator part forming the bottom of the condenser casing is provided a pressure reducing opening 25. The refrigerator 23 comprises an internal, cylindrical part 26 and an external part 27 surrounding said part 26. A ring chamber is left between the two parts 26 and 27. In order to facilitate the transmission of heat to the refrigerating medium it is advisable to provide the outer refrigerating part 27 in the manner shown in Fig. 4 with radial ribs or gills 28. The pressure reducing opening 25 discharges into the upper portion of the chamber 28. The ring chamber left between the two parts 26, 27 communicates at its lower end with the chamber 28 of the refrigerator, while at the top it is put into communication with the suction chamber 14 provided within the cylindrical compressor casing 10 by means of a conduit 29.

The condenser casing 5 is also surrounded by a casing 30 provided on its inner side with helical ribs. The ring space left between the two casings 5 and 30 forms a water jacket. To the lower end of this jacket is connected a supply-pipe 32 for the cooling water. 33 denotes an outlet-pipe for this water communicating with the upper portion of the water jacket.

The fitting of the hereinbefore described machine in any existing refrigerator or in any to be built for special requirements in the manner shown in Fig. 5 may be effected in a very simple manner. To this end the complete machine and electric motor is simply placed in the opening 34 (Fig. 5) in the top of the refrigerator.

The hereinbefore described electric driven refrigerating machine works as follows:

The refrigerating medium—and as such a medium chlorid of methyl for instance may be used—is drawn by the piston 7 of the compressor from the suction chamber 14 in a gaseous state into the suction side of the cylinder 8 on the momentary opening of the slots 19 during the oscillating movement of the compressor. This medium is then compressed to a pressure corresponding to the cooling water temperature and passes hereupon into the bottom pressure chamber 15. From here it flows through the rising pipe 20 into the top pressure chamber 16 and then at first through the pipe 21 into the ring space 22 surrounded by the water jacket and afterward into the condenser chamber 24 where it is liquefied.

60 The liquid refrigerating medium flows through the pressure reducing opening 25 into the internal chamber 28 of the refrigerator. The great reduction of pressure taking place greatly lowers the temperature of the refrigerating medium, which in conse-

quence of the reduction of pressure again evaporates extracting thereby the requisite amount of heat from the surrounding atmosphere or brines. As already stated, the ribs or gills 28 facilitate during this process the transmission of heat to the refrigerating medium. Owing to this evaporation the temperature of the surrounding atmosphere or brine is reduced, therefore "cold is produced." The evaporated refrigerating medium is then again drawn through the pipe 29 into the suction chamber 14, from where it is afterward drawn by the compressor and allowed to repeat the cycle just described.

80 The heat absorbed by the refrigerating medium is transmitted to the cooling water circulating in the ring space between the casings 5 and 30. The helical ribs of the casing 30 assist in a most effective manner 85 the cooling action of the water.

As shown, all working parts are inclosed in an airtight manner. Thus, it is only necessary to fill the machine with the requisite quantity of refrigerating medium before 90 it is forwarded; a leakage of this medium is not possible and therefore no subsequent filling is necessary. The starting and stopping of the machine is also very simple.

95 The lubrication of the working parts in an automatic manner is attained by the use of the top pressure chamber 16 as an oil tank and by feeding the lubricant from this chamber to the working parts by means of suitable channels or the like. The dripping 100 oil is collected in the bottom pressure chamber 15. As soon as the level of the oil in this chamber reaches the lower end of the rising pipe 20 the refrigerating medium flowing at a high speed into this pipe draws 105 lubricant with it into the chamber 16, where the oil easily separates by gravity from the gaseous medium. The lubricant is stored up in this chamber 16.

110 What I claim is:

1. In an electric driven refrigerating machine, in combination, an electromotor comprising an external stator and an internal rotor, a compressor, means for driving the compressor from the end of the rotor shaft, the compressor being mounted in a cylindrical casing, a condenser casing surrounding the latter, a thin steel-cap of low electric conductivity put over the rotor and joined in an airtight manner to said condenser casing, a pressure reducing opening in the bottom of the condenser chamber, a refrigerator into which exhausts said opening, a connection between the refrigerator and a suction chamber provided in the cylindrical compressor casing, the latter comprising besides said suction chamber a number of superposed pressure chambers, the compressor exhausting into the lowermost of these pressure chambers, and a rising pipe 125 130

leading from the lowermost part of said pressure chamber into a superposed pressure chamber.

2. In an electric driven refrigerating machine, in combination, an electromotor comprising an external stator and an internal rotor, a compressor, means for driving the compressor from the end of the rotor shaft, the compressor being mounted in a cylindrical casing, a condenser casing surrounding the latter, the latter again surrounded by a cooling water jacket, a thin steel-cap of low electric conductivity put over the rotor and joined in an airtight manner to said condenser casing, a pressure reducing opening in the bottom of the condenser chamber, a refrigerator into which exhausts said opening, a connection between the refrigerator and a suction chamber provided in the cylindrical compressor casing, the latter comprising besides said suction chamber a number of superposed pressure chambers, the compressor exhausting into the lowermost of these pressure chambers, and a rising pipe leading from the lowermost part of said pressure chamber into a superposed pressure chamber.

3. In an electric driven refrigerating machine, in combination, an electromotor comprising an external stator and an internal rotor, a compressor, means for driving the compressor from the end of the rotor shaft, the compressor being mounted in a cylindrical casing, a condenser casing surrounding the latter, a thin steel-cap of low electric conductivity put over the rotor and joined in an airtight manner to said condenser casing, a pressure reducing opening in the bottom of the condenser chamber, a refrigerator with double walls, the pressure reducing opening exhausting into the upper portion of the inner chamber of the refrigerator while the outer chamber communicates at the lower end with said inner chamber and at the upper end with a suction chamber provided in the cylindrical compressor casing, the latter comprising besides said suction chamber a number of superposed pressure chambers, the compressor exhausting into the lowermost of these pressure chambers, and a rising pipe leading from the lowermost portion of said pressure chamber into a superposed pressure chamber.

4. In an electric driven refrigerating machine, in combination, an electromotor comprising an external stator and an internal rotor, a compressor, means for driving the compressor from the end of the rotor shaft, the compressor being mounted in a cylindrical casing, a condenser casing surrounding the latter, the condenser casing being again surrounded by a cooling water jacket, a thin steel-cap of low electric conductivity put over the rotor and joined in an airtight manner to said condenser casing, a pressure re-

ducing opening in the bottom of the condenser chamber, a refrigerator with double walls, the pressure reducing opening exhausting into the upper portion of the inner chamber of the refrigerator while the outer chamber communicates at the lower end with said inner chamber and at the upper end with a suction chamber provided in the cylindrical compressor casing, the latter comprising besides said suction chamber a number of superposed pressure chambers, the compressor exhausting into the lowermost of these pressure chambers, and a rising pipe leading from the lowermost part of said pressure chamber into a superposed pressure chamber.

5. In an electric driven refrigerating machine, in combination, a vertical electromotor having an external stator and an internal rotor, a compressor arranged below this motor, means for driving the compressor from the bottom end of the rotor shaft, said compressor being mounted in a casing arranged coaxially to the electromotor, this casing surrounded by a condenser casing, a thin steel-cap of low electric conductivity put over the rotor and joined in an airtight manner to said condenser casing, a pressure reducing opening in the bottom of the condenser chamber, a refrigerator provided below the condenser casing and arranged coaxially therewith, the pressure reducing opening discharging into this refrigerator, a connection between the refrigerator and a suction chamber provided in the cylindrical compressor casing, the latter comprising besides said suction chamber a number of superposed pressure chambers, the compressor exhausting into the lowermost of these pressure chambers, and a rising pipe leading from the lowermost part of said pressure chamber into a superposed pressure chamber.

6. In an electric driven refrigerating machine, in combination, a vertical electromotor having an external stator and an internal rotor, a compressor arranged below this motor, means for driving the compressor from the end of the rotor shaft, said compressor being mounted in a casing arranged coaxially to the electromotor, this casing surrounded by a condenser casing, a thin steel-cap of low electric conductivity put over the rotor and joined in an airtight manner to said casing, a pressure reducing opening in the bottom of the condenser chamber, a refrigerator with double walls provided below the condenser casing and arranged coaxially therewith, the pressure reducing opening discharging into this refrigerator, a connection between the refrigerator and a suction chamber provided in the compressor casing, the latter comprising besides said suction chamber a number of superposed pressure chambers, the com-

pressor exhausting into the lowermost of these pressure chambers, and a rising pipe leading from the lowermost part of said pressure chamber into a superposed pressure chamber.

7. In a refrigerating machine, the combination with a casing having an evaporating chamber; of a suction chamber communicating therewith, a bottom pressure chamber, a compressor between the two chambers, a top pressure chamber for containing oil, and means connecting said top and bottom chambers whereby oil collecting in said bottom chamber will be carried by the compressed refrigerant discharged from the compressor into said top chamber.

8. In a refrigerating machine, the combination with an evaporating chamber; of a co-axial suction chamber, two superimposed pressure chambers, a compressor between the suction chamber and one of said pressure chambers, a condensing chamber, an annular cooling space surrounding said chambers, a cooling jacket surrounding said cooling space and a valveless pressure reducing orifice discharging condensate from the

condensing chamber into said evaporating chamber.

9. In a self-contained refrigerating machine, an armature and its shaft, a plurality of chambers co-axial with said armature and shaft, a compressor driven from said shaft, a water jacket surrounding several of the aforesaid chambers and spaced therefrom, means to inclose the armature gastight and a stator surrounding said means.

10. In a self-contained refrigerating machine, two superposed pressure chambers and a suction chamber between them, a compressor between the suction chamber and the lower pressure chamber, a driving shaft concentric with said chambers, a pipe between the two pressure chambers whose lower end is slightly above the bottom of the lower pressure chamber and whose upper end is above the oil level in the upper pressure chamber, and means to supply oil from said upper pressure chamber to said shaft and compressor.

In testimony that I claim the foregoing as my invention I have signed my name.

HEINRICH ZOELLY.
